UNITED STATES PATENT OFFICE.

MARTIN C. NEUNER, OF LOS ANGELES, CALIFORNIA, ASSIGNOR TO THE NEUNER SPECIALTY BOOK COMPANY, OF LOS ANGELES, CALIFORNIA, A CORPORATION OF CALIFORNIA.

LOCKING-BAR FOR LOOSE-LEAF RECORDS, &c.

SPECIFICATION forming part of Letters Patent No. 792,840, dated June 20, 1905.

Application filed July 29, 1903. Serial No. 167,379.

To all whom it may concern:

Be it known that I, MARTIN C. NEUNER, a citizen of the United States, residing at Los Angeles, in the county of Los Angeles and State of California, have invented a new and useful Locking-Bar for Loose-Leaf Records and the Like, of which the following is a specification.

This invention relates to a locking-bar adapted to be clamped onto posts which are used in loose-leaf books.

In a former application of mine I have shown a locking-bar comprising two members provided with registering post-receiving recesses and slidale relatively to each other to effect a clamping of the posts.

The present invention is an improvement over the former in that it is of much simpler construction, of more compact form, that is thinner, lighter in weight, and may be manufactured at slight expense compared to the former bar.

The bar forming the present invention is adapted to be clamped to the posts at any point and is adapted to be used between the covers to keep sheets which are on the posts in compact form, or it may be fastened to the cover or to the inside of the back of the book or other covering for the loose leaves, or it may be attached to the outside of the cover.

The uses of the bar are many, it being adapted for use in any book or loose-leaf record device where posts are used.

The securing of the bar to the posts is accomplished very quickly, and the unlocking is accomplished as readily.

The accompanying drawings illustrate the invention, and referring to the same, Figure I is a perspective view showing a part of a book open, the locking-bar being applied in two places. Fig. II is a side elevation of a portion of the locking-bar. Two clamps are embraced in the part shown. The parts are shown in section, and one clamp is raised and the other closed in locking position. Fig. III is a perspective view of a loose-leaf binder, showing another application of the locking-bar. Fig. IV is an end elevation of the book-

back of Fig. I, showing how the bar may be hinged thereto. Fig. V is a section through the bar on line V V of Fig. II.

In the drawings I have shown three applications of the bar; but other uses may suggest themselves to those interested in the art, and it should be understood that I do not limit myself to any particular application of the bar, as its uses and the methods for attaching the bar to the cover or to parts other than the posts are manifold.

The invention comprises a bar 1, which is provided with one or more notches 2. The mouth of the notch is preferably the wider part of the notch, and one wall of the notch is cut back to form a shoulder 3. The wall around the inner part of the notch is round to form a good fit for the post 4.

5 is a clamp pivoted to the bar, as at 6, and provided with a finger 50 for operating it and with a toe 7, between which toe and the pivotal point is a notch 8. The toe 7 is curved eccentrically to the pivot 6, and when in its closed or operative position it projects forward beyond a line through the pivotal point 6 and the inner end of the notch 4 or the post when it is in the notch, said line extending longitudinally of the bar.

By locating the pivot at one side of the inner end of the notch and causing the toe to engage with the post upon the side opposite thereto and from the rear or bottom of the notch the toe will continue to engage with the post even if the bar should be moved to the rear and it would be drawn into tighter engagement therewith the more the bar were drawn to the rear. In this manner the bar will be prevented from being withdrawn from the posts until after the clamps have been released, even though the parts should become worn, so as to permit more or less play between the post and the shoulder. At the same time this construction of the clamps and notches permits of the bar being secured to or released from the posts with but a slight movement of the clamp, and when so secured the handle of the clamp lies substantially lengthwise of the bar, so as to be as much out

of the way as possible, which is a very important consideration, and especially when the device is used as a book.

- The bar is applied to the posts, so that the 5 posts lie in the notches 2, then the clamp is depressed and the toe 7 rubs against the side of the post and draws the bar tightly against the post, so the shoulder 3 lies in front of the post and faces the gripping edge of the clamp.
- 10 The clamp is beveled to an edge 9, (see Fig. V,) so that when the clamp is set the edge 9 bites into the post, and thus the shoulder 3 and bite of the clamp holds the bar securely on the post.
- 15 By pivoting the clamp flatwise upon the bar, so as to be movable in a plane parallel with the side of the bar, the engagement of the sharp edge with the post is in a line with the length of the edge, which will prevent its be- 20 ing dulled or broken when moved into or out of engagement with the post to such an extent as would be the case if it were pivoted, so as to swing toward and from the side of the bar.
- 25 As leaves are added to the posts the bar is adjusted upon the posts so that the clamp will bite a new part of the post, and slipping is thus positively prevented.

The bar may be removed from the posts by 30 throwing up the clamps.

The number of notches in the bar and clamps therefor may be, as desired, dependent upon the number of posts; but it is obviously not necessary to employ a clamp for each and 35 every post, although a notch must be provided for each post.

By employing a series of independently-operative clamps a very simple, cheap, and efficient locking device is provided. The 40 leaves can be fastened together more tightly when clamps are provided, which operate independently of each other, because the operator may use one hand to press together the leaves at the point to be gripped while operating the clamp adjacent such point with the other hand.

In Fig. I the bar is shown as clamped to the posts intermediately to hold the sheets compactly pressed together. The bar is also in 50 the same view shown as hinged to the back, the clamps engaging the posts near their ends.

Fig. IV shows a hinge 11, fastening the bar to the back 12.

In Fig. III the bar is shown applied outside 55 the cover of a binder and gripping the posts intermediately, and as sheets are added or removed the bar may be adjusted up or down to lie close against the cover.

What I claim is—
60 1. A locking-bar provided with shouldered

notches, and means for contracting the space between the shoulder of each notch and a point directly opposite said shoulder.

2. A locking-bar provided with shouldered notches, and means movable in a plane parallel 65 with the side of the bar for contracting the space between the shoulder of each notch and a point directly opposite said shoulder.

3. A locking-bar provided with shouldered notches, and a clamp pivotally secured to the 70 bar at one side of each notch and adjacent to its shoulder and provided with a portion movable in a plane parallel with the side of the bar into a position on the side of the notch diametrically opposite the shoulder and in ad- 75 vance of a line longitudinally of the bar and through said pivot and the inner end of the notch.

4. A locking-bar provided with shouldered notches, and a clamp pivotally secured to the 80 bar at one side of the notch and adjacent to its shoulder and movable in a plane parallel with the side of the bar, the pivotal point of the clamp being on a line longitudinally of the bar and through the inner end of the notch 85 said clamp being provided with an eccentric toe adapted to be moved into a position on the side of the notch opposite the shoulder, whereby the space of the notch opposite said shoulder is contracted.

5. A locking-bar provided with shouldered notches, and a clamp pivotally secured flatwise to the bar adjacent to each shoulder and movable in a plane parallel with the side of the bar, the pivotal point of the clamp being on a 95 line longitudinally of the bar and through the inner end of the notch said clamp being provided with an eccentric toe adapted to be moved into a position on the side of the notch opposite the shoulder, whereby the space of the notch opposite the shoulder is contracted, the inner edge of said toe being inclined to form a cutting edge.

6. The combination, with the back of a loose-leaf holder, of a notched locking-bar pivotally 100 secured thereto, and means on the bar at each notch for engaging with the posts of the holder and holding each of them behind its respective shoulder, thereby clamping the bar to the posts.

In testimony whereof I have signed my name to this specification, in the presence of two subscribing witnesses, at Los Angeles, in the county of Los Angeles and State of California, this 22d day of July, 1903.

MARTIN C. NEUNER.
